WELL CLEANER

Frederick Nathaniel Schneringer, South Whittier,
Calif., assignor to C. C. Taylor, Whittier, Calif.

Application March 22, 1933, Serial No. 662,103

7 Claims. (Cl. 166—20)

This invention relates to well cleaners for removing débris, rotary mud or other impediments to flow from producing strata into a well hole, and in addition, and more particularly, to a means for removing clogging obstructions from the openings through perforated well casings, which casings are frequently employed in oil producing strata and are commonly known as well screens or strainers.

5 A principal object of the present contribution to the art is to provide a device which may be inserted into a well casing and lowered to the screen or strainer length thereof, where it may be operated to force out by powerful suction, débris, closely packed sand, paraffin, or other deposits clogging the seepage holes from the producing formation, or between it and the casing, as well also as those impeding passage through screen or strainer openings, in order to permit a 10 free seepage of the product of the well into the casing.

10 It is also a particular object of the present invention to provide a device of the character described in which both pressure and suction from within an extension of the tubing are employed to first force outward and then draw such obstructions into the casing, where they may later be removed or treated by other means well known to the art, rather than to force and leave them 15 outside of the casing where they may wholly or partially seal off the producing strata, or, in case of the screen, may again return to obstruct seepage therethrough.

20 A still further object is the provision of means to accomplish the above objects which may be installed for operation at any desired level in the well and which may be moved from such position to a new location with a minimum of effort on the part of the operator.

25 Economy of manufacture and of service, facility of handling, surety of action and efficiency of operation are also important objects and qualities of the present invention.

30 I attain the above mentioned objects by the devices illustrated in the accompanying drawing in which—

35 Fig. 1 is a sectional view of a well casing-screen, my invention (shown positioned within said casing-screen) being illustrated in elevation;

40 Fig. 2 is a view of the well casing-screen similar to Fig. 1, with said invention shown therein illustrated in longitudinal section;

45 Fig. 3 is a sectional view on line 3—3 of Fig. 2;

50 Fig. 4 is a like view on line 4—4 of Fig. 1.

Similar indicating letters and numerals refer to similar parts throughout the several views.

Elements comprising the subject-matter involved in the present invention may for brief perspicuity be described or classified as follows: 5 A indicates a well-screen in the form of a perforated casing, the perforations therein being designated by a; B represents any common form of well-tubing, to which is rigidly attached, snugly but slidably fitting the well casing, any suitable packing device C many forms of which are known in the art and the specific construction of which, being no part of the present invention, need not be further described. D is an upper packing device (like and similar to C) said upper 10 packing element D being rigidly attached to a sleeve E, through which tubing B is adapted to closely but slidably fit. Sleeve E carries means, later to be specifically described, for locking it, with its attached packing element, at any selected point within the well casing, which point, for operative purposes, may be immediately above any series of perforations desired to be cleaned.

Lower packing element C is secured adjacent the lower end of a length of tubing B by abutting 25 against an annular flange 1 which is welded or otherwise rigidly secured to said tubing, said packing element C being held upward in contact with its abutment flange 1 by a flanged tubing-coupling member 2 screw-threaded on the lower 30 end of said length of tubing.

The upper packing element D is mounted on the lower end of the sleeve E being held in such position against upper abutment flange 3 on said sleeve by collar 4, which is screw threaded on the 35 lower end of said sleeve E. To the upper end of sleeve E is screw threaded a slip expander 5 having a plurality of inclined faces 6 each carrying a dove-tailed tenon 7 slidably fitting a corresponding mortise on the slip hereinafter described.

Slip expander 5 is centrally bored to the same inner diameter as sleeve E, on which, when screwed in place it becomes a part, such bore being enlarged in its upper portion to provide a 45 stuffing-box in which expansible material 8 is compressed by a gland 9 in any well-known conventional manner.

On the exterior of tubing B above the lower packer C, studs 10—10 are formed, which studs 50 constitute means for detachably securing sleeve E with its packer D, slip expander 5 and its associated mechanism about to be described to said tubing B so as to permit manipulation from the top of the well to anchor and release, as desired, 55

the upper packer D, as hereinafter more fully described.

11-11 indicate slips the inner inclined faces of which carry mortise grooves into which the dove-tailed tenons 1 (hereinbefore described) on the inclined faces 6 on slip expander 5 slidingly engage, said dove-tailed and mortised engagement of the slips and their expander being employed to hold the slips in contact with their expander-faces when not in wedged position between the expander and the casing. The upper faces of the slips 11-11 carry a series of downwardly directed teeth 12 adapted when the parts are in position shown in Fig. 2 of the drawing to bite into the interior wall of the casing and hold the parts, appended to the slips and their expander, in anchored position within the casing.

Slips 11-11 are pivotally connected through depending lugs, formed on their lower ends, by pins 13-13 to links 14-14, and the lower ends of links 14-14 are pivotally secured to extending lugs on sleeve 15 by pins 16-16.

A plurality of bowed springs 17-17, designed normally to expand outwardly at their centers so as to contact with the walls of the casing, are attached at their upper ends in any suitable manner, as by screws 18 to lateral extensions on sleeve 15a, said bowed springs 17-17 being also likewise secured at their lower ends by screws 19 to extensions 21 on sleeve 20. Both of sleeve members 15a and 20 surround and slidingly engage sleeve E, and sleeve 15 in turn slidingly engages sleeve 15a. 22 is a bayonet slot cut from the lower edge of sleeve 20, which engages a stud 35 23 carried by sleeve E.

24 indicates an open port through tubing B and 25 a back-pressure valve, which may be of any well known form, controlling a port 26 in a tubing coupling-member 27. 28 is a screw plug 40 to permit access to the valve for adjustment or cleaning.

29 designates a partition inside of tubing B, closing the bore of said tubing; and 30 and 31 are open ports in tubing B above partition 29 to 45 permit the free flow of fluid into and out of the tubing B above the partition 29.

The installation and operation of the device are as follows: The assemblage of various parts described, and as shown in Fig. 1, with the anchoring mechanism and its associated elements 50 through which tubing B extends is lowered into the casing to a point where the upper packer D will be above a series of perforations, usually beginning with a series at the bottom of the screen, desired to be cleaned. To anchor the upper packer D in such location, the tubing B (at the top of the well) is turned to the right, the bowed springs 17-17, by their frictional engagement with the inner wall of the casing, retarding 55 corresponding movement of the slip-mechanism and its associated parts, so that the stud 23 is moved laterally to the left in the bayonet-slot 22, and in a position at the top of the vertical portion of the slot so that a further slight downward movement of sleeve E imparted by lowering tubing B, will disengage stud 23 from slot 22, the bowed springs 17-17 by their frictional engagement with the casing, again functioning to assist in such change of relative position.

70 When stud 23 is out of bayonet-slot 22, the slips are relatively higher on the inclined faces of the slip-expander 5, and a slight further downward movement of the tubing, communicated to slip-expander 5, will wedge slip-expander 5 between slips 11-11, and the teeth 12 of the latter

will bite into the casing and thus anchor sleeve E with its attached upper packer D to the casing.

With the upper packer D thus anchored in the casing, the reciprocation of the lower packer C, within a predetermined narrow range, by the alternate raising and lowering of the tubing B to which said lower packer C is attached, will cause said lower packer to act in a manner similar to a pump plunger. When, for instance, the lower packer C is moved downward relative to the upper packer D by the manipulation of the tubing at the top of the well, there will be created a powerful suction from the outside of the casing through perforations and into the chamber between the two packers; and when the lower packer C is raised the compressive tendency in the chamber between the two packers will be neutralized by the opening of the valve 25, when pressure in the chamber between the two packers will be expanded through port 24 and said back pressure valve 25. On the other hand, when the lower packer C is pushed downward, valve 25 will close, thus necessitating relief of the partial vacuum in the chamber between the packers by suction through the perforations in the casing. Said downward movement of packer C will also cause fluid in the casing below said packer to pass outwardly through perforations below packer C and up and back into the casing through the perforations above the said packer.

Open ports 30 and 31 permit liquid to enter and leave the portion of tubing B above partition 29, that is to say, when the tubing at the points of location of said ports 30 and 31, is below the fluid level in the well, fluid will flow into the 35 tubing therethrough, and when the tubing at the location of the cleaning device is raised above the fluid level any fluid in the tubing will flow out and back into the well.

It will be obvious that various modifications of 40 the design and arrangement of the various parts of my invention may be employed without departing from the spirit thereof.

What I claim and desire to cover by Letters 45 Patent is:—

1. In a well cleaning device, the combination of a pair of pistons adapted to snugly but slidingly fit the interior of a perforated well-casing, means to anchor one of said pistons within said casing at any desired point, means adapted to reciprocate the other of said pistons with respect to the first after the latter has been anchored, said reciprocating means between said pistons having a port communicating with the space below the lowermost thereof, and valvular means controlling said port adapted to release compression within the chamber between the pistons.

2. In a device of the character described, a pair of pistons adapted to snugly but slidingly fit the interior of a perforated well-casing, one of said pistons carrying means to anchor it at any desired point within said well-casing, means connected to the other of said pistons adapted to reciprocate it within said casing with respect to its companion piston after the latter has been anchored within said casing, said reciprocating means having a port for intercommunication of the space between said pistons with the space within said casing not between said pistons and means including a valve to preserve suction in the space between said pistons during the suction stroke and to release compression during the return to position for the next pumping stroke.

3. In a well cleaning device, the combination 71

- of two packing elements, each adapted to snugly but slidingly fit the interior of a perforated well-casing, the uppermost of said packing elements carrying means adapted to anchor it at any predetermined point within said casing, the other of said packing elements being adapted to be reciprocated with respect to the first of said packing elements by means communicating from the top of the well, said reciprocating means between 5
- 10 said pistons having a port communicating with the space below the lowermost of said pistons, and valvular means controlling said port adapted to release compression within the chamber between said pistons.
- 15 4. In a device of the character described, a well-casing packer secured to a string of well-tubing, a second well-casing packer slidable on said tubing and carrying means adapted to anchor it at a selected point within a perforated 10 well-casing, a port through said tubing at a point located between said casing packers when the same are in operative position and means controlling said port to relieve compression between said packers during relative movement thereof.
- 20 25 5. In a well cleaning device, a pair of packers adapted to snugly but slidingly fit the interior of a perforated well-casing, one of said packers being attached to a string of well-tubing, the other of said packers being slidable on said tubing and 20 having associated with it means to anchor it at any desired point within the well-casing, said tubing between said packers having a port inter-communicating with space between said packers and space within said casing not between said packers, and means comprising a valve controlling said port to preserve suction and release compression between said packers during movement of one of said packers relative to the other. 5
6. In a device of the character described, a pair of packers adapted to snugly and slidingly fit the interior of a perforated well casing, one of said packers being attached to a string of well-tubing extending to the top of the well, the other of said packers being slidable on said well-tubing and having associated with it means to anchor it 15 at any desired point within said well-casing, a partition in said tubing dividing the same laterally adjacent the unanchored packer, a port in said tubing below said partition and a back pressure valve controlling said port. 20
7. In a device of the character described, a well casing packer secured to a string of well tubing, a second well casing packer slidable on said tubing and carrying means adapted to anchor it at a selected point within a perforated well cas- 25 ing, and means for relieving compression while preserving suction during relative movement of one of said packers with relation to the other.

FREDERICK NATHANIEL SCHNERINGER. 30
